UNITED STATES PATENT OFFICE.

ERWIN B. LOEWENBACH AND CHARLES M. HUNTER, OF MILWAUKEE, WISCONSIN,
ASSIGNORS TO E. B. L. SHOE MFG. CO., OF MILWAUKEE, WISCONSIN.

SHOE.

1,130,305.

Specification of Letters Patent.

Patented Mar. 2, 1915.

Application filed March 18, 1914. Serial No. 825,478.

To all whom it may concern:

Be it known that we, ERWIN B. LOEWENBACH and CHARLES M. HUNTER, both citizens of the United States, and residents of Milwaukee, in the county of Milwaukee and State of Wisconsin, have invented certain new and useful Improvements in Shoes; and we do hereby declare that the following is a full, clear, and exact description thereof.

10 Our invention refers particularly to the manufacture of shoes of the "Bal" pattern and has for its object to provide simple, economical and effective patterns for shoes of the type mentioned, whereby the cost of manufacture is materially reduced, while at the same time the life and comfort of the shoe is materially increased. By the peculiar formation of the blanks great reduction in the waste of the material from which 20 said blanks are cut is had.

Specific objects of our invention are to provide a vamp and quarter pattern that is cut away at the front of the vamp to the top of the quarter to form a lace-stay opening 25 space, whereby material is saved. It is also contemplated to cut away the toe of the vamp in some instances, whereby a further saving in the stock is had; to provide a combination vamp, tip and lace-stay strip, 30 which, when sewed to the vamp and quarter completes the same forming a lace-stay of single thickness in contradistinction to a lace-stay of double thickness as in the case of the ordinary "Bal" pattern; to provide 35 in some instances a quarter and vamp blank embodying the features of our invention wherein said quarter and vamp are separate members, whereby economy in the cut is effected, it being well known that the smaller 40 the parts forming the blank the more economically they may be taken from the hide or stock from which blanks are cut. Hence the saving in the waste is proportionately greater.

45 With the above and other minor objects in view the invention consists in certain peculiarities of construction and combination of parts as hereinafter set forth with reference to the accompanying drawings and subsequently claimed.

In the drawings Figure 1 represents a combined vamp and quarter blank cut in accordance with our invention, the dotted lines indicating the change or form over that of 50 the ordinary "Bal" type of pattern; Fig. 2,

a view of a combination tip and lace-stay embodying the features of our invention; Fig. 3, a back stay pattern; Figs. 4 and 5 represent a modified form of our improved pattern, whereby the vamp and quarter are 60 cut in separate pieces, it being within the scope of our invention to cut the vamp portion in some instances with or without a tip; Fig. 6, a view of a gusset or tongue blank employed in forming a shoe embodying the 65 features of our invention; Fig. 7, a diagrammatic plan view showing the manner of securing the combination tip and lace-stay to a pair of the vamp and quarter patterns which, as shown, are seamed together at the 70 front portions of the vamp members, and Fig. 8 represents an elevation of a completed shoe upper made in accordance with our invention, one of the lace-stays being 75 folded over to more clearly illustrate structural features.

Referring by characters to the drawings, 1 represents a quarter portion and 2 the vamp portion of a pattern having the tip of the vamp cut off upon the line 3. The 80 back portion of the vamp is cut downwardly as shown at 4 and from this point the quarter is cut away as shown at 5' to parallel the lace-stay, whereby an open space is formed to the top of the quarter. Two of such 85 blanks are utilized in forming a shoe upper and they are connected at the heel seat by a tapered heel stay-blank 1", as shown in Fig. 3, which stay-blank forms no part of our invention.

Fig. 2 illustrates a tip 6 having extended therefrom lace-stay members 7, 7, as shown, the said tip and stay members being preferably formed in a single piece.

Fig. 4 represents a blank similar to that shown and described in connection with Fig. 1 of the drawings with the exception that the quarter 1' is cut in a separate piece from the vamp 2'. In this instance the back of the vamp is cut away at 4' and the quarter 100 being stitched to the straight edge 8 of the vamp, its front edge 5' will thus form an open space for the lace-stay.

Fig. 6 illustrates a tongue blank 9 having tabs 9' that extend rearwardly from 105 the body of the tongue.

Fig. 7 shows a pair of the combination vamp and quarter patterns stitched together, as indicated at a. When these members are stitched together they form a lace- 110

stay opening *b* as shown, which opening results from the parallel edges 5' of the quarter, a portion of said edges being shown in full lines and the forward portion in dotted lines. After the vamp and quarter patterns have been stitched together, as shown at *a*, the tip 6 is fitted over the forward edges 3 of the vamp and stitched thereto to form the toe of the vamp, which toe, in this instance, will consist of a single piece of leather. The stay-pieces 7, 7, of the blank are then lapped over the edges 5' and stitched as shown, whereby the divided stay-pieces close the opening *b* and form a single thickness eyelet or stay-strip. The said lace-stay thus stitched completes the quarter without a double thickness of leather, as stated. The gusset blank is then inserted within the inside of the vamp and quarter about the lace opening and stitched in such manner that the tabs 9' will register with the inner faces of the stay-strips and overlap the faces of the cut away portions upon the lines 5' to thus conceal the seam between the single lace-stay piece and said quarter, giving the upper an interior finish and adding a thin thickness or lining to the thin stay-piece or eyelet row.

It is obvious that we may, without departing from the spirit of our invention, either use a double thickness of toe in which case the front of the vamp would not be cut away, or we may sever the front, as shown in Fig. 1, and complete the vamp with a single thickness of leather by stitching thereto the tip 6.

Fig. 8 represents the finished shoe upper wherein the quarter and vamp portions were cut in separate blanks and stitched together upon the line 8', as shown, but it is understood that the upper may be as effectually constructed from a blank such as shown in Fig. 1, wherein the vamp and quarter are in one piece.

By the peculiar arrangement of cut, as shown by the blanks as previously described, in practice it has been found that

approximately a saving of 20% is effected in the cut of the leather due to the fact of the peculiar cut of said blank with reference 50 to the stay-piece opening and cutting off of the front of the vamp to form a toe of single thickness.

We claim:

1. A shoe upper formed from a pair of 55 blanks stitched together at their front and rear ends each blank comprising a vamp portion and a quarter portion cut away to form a lace-stay opening that extends to the top of the quarter, and a blank comprising 60 a tip having lace-stay strips extending therefrom, the tip portion being sewed to the vamp to form a toe and the lace-stay portions lapping the edges of the cut away portions to which they are sewed to form a 65 single thickness of lace-stay.

2. A shoe upper comprising a vamp and quarter cut away approximately the width of the lace-stay, and a lace-stay secured to the cut away edges of the vamp and quarter 70 to form a single thickness of lace-stay.

3. A shoe upper comprising a vamp and quarter cut away approximately the width of the lace-stay, and a lace-stay secured to the cut away edges of the vamp and quarter 75 to form a single thickness of lace-stay, and a tongue secured to the vamp and quarter having tabs overlapping the inner faces of the lace-stay and quarter to conceal the seam between said lace-stay and quarter. 80

4. A shoe upper comprising a vamp and quarter, the vamp and quarter being cut away to form a lace-stay opening the width of a standard lace-stay.

In testimony that we claim the foregoing 85 we have hereunto set our hands at Milwaukee in the county of Milwaukee and State of Wisconsin in the presence of two witnesses.

ERWIN B. LOEWENBACH.
CHARLES M. HUNTER.
